UNITED STATES PATENT OFFICE.

HARRY C. MALLORY, OF BELLPORT, NEW YORK.

DIAPHRAGM.

1,099,855.

Specification of Letters Patent.

Patented June 9, 1914.

Application filed October 4, 1911, Serial No. 652,740. Renewed November 11, 1913. Serial No. 800,405.

To all whom it may concern:

Be it known that I, HARRY C. MALLORY, of Bellport, Suffolk county, New York, have invented a new and useful Improvement in 5 Diaphragms, which invention is fully set forth in the following specification.

This invention relates to improvements in diaphragms adapted to be actuated by fluid pressure, as in steam traps, damper regulators, atmospheric motors, and the like, and more particularly to diaphragms made of a 10 single sheet of metal characterized by having collapsible folds and giving extensive movement while avoiding buckling and 15 other defects heretofore met with in flat diaphragms.

Regulators of the diaphragm type, as distinguished from those of the bellows or accordion type, have been in common use for a 20 long time, and their surfaces have been given corrugations with a view of increasing their flexibility, but these corrugations have not been given the proper design and character to produce elasticity enough to 25 secure any wide range of movement, and to avoid buckling and lost motion. In flat diaphragms as heretofore constructed with corrugations, the binding of the diaphragm when subjected to fluid pressure takes place 30 in a predominating measure at the annular bends which flatten under this pressure. No great amount of flattening of these bends, and consequent motion of the diaphragm, can take place without giving a 35 permanent set to the diaphragm, which unfits it for usefulness in many situations. Diaphragms which rely largely for outward motion on the capacity of the bends for flattening are found to buckle around the point 40 of attachment of the power-transmitting means. This means lost motion when fluid pressure is acting to force the diaphragm out. The valve stem or other power-transmitting means does not therefore receive the 45 extent of movement it otherwise should have, if there were no buckling.

It is the object of this invention to overcome, in large part or entirely, the objections of the character above described, and to 50 provide a diaphragm which has a wide range of motion more nearly approaching that of corrugated collapsible and expandable cylinder or bellows, and which is practically free from objections found in the use 55 of flat diaphragms as heretofore constructed.

I have discovered that by constructing the diaphragm with corrugations such that the bending is transferred from the curved ridges of the corrugations to the flat or slightly curved connecting portions, a marked increase in the motion, power and life of the diaphragm is secured, while avoiding lost motion by buckling. I accomplish this result by making the portions connecting the bends or ridges of the convolutions of sufficient extent to constitute the entire or substantially entire bending part of the diaphragm. While I may make all parts of the corrugations of the same 70 density of metal, I prefer to stiffen the bends, as by providing a greater hardness or compactness of metal along these points. The portions of the convolutions uniting the bends are less dense, and are more flexible, 75 and form annular rings, which may or may not be parallel with each other, and may be normal to or inclined to the face of the diaphragm.

The inventive idea may receive a variety 80 of mechanical expressions, some of which are illustrated in the accompanying drawings, which are intended as assisting in the description and for illustration only, reference being had to the claims for defining the 85 limits of the invention.

In the drawings, Figure 1 is a view, partly in vertical section and partly in elevation, showing a damper regulator provided with my improvement; Fig. 2 is a top 90 plan view, taken below the line 2-2 of Fig. 1; Fig. 3 is an enlarged detail of the diaphragm; and Figs. 4 and 5 are vertical sectional views of thermosensitive vessels provided with different embodiments of my improvement.

In Figs. 1, 2 and 3, I have illustrated my collapsible diaphragm in a form particularly serviceable for heavier kinds of work, such as operating dampers. The diaphragm 1 is made of sheet metal, such as sheet iron, brass or bronze, which possesses strength and flexibility, and is provided with a plurality of concentric folds or convolutions in which the troughs 2, 2, of one set of folds are connected with the crests 3, 3, of the adjacent folds by annular portions 4, 4, of such depth that movement of the diaphragm out of or into its normal flat position takes place by virtue of the collapsible and extensible action in the connecting portions more than in the bends 2, 3.

As shown in cross-section, the connecting portions are not quite parallel, and the metal is not uniformly distributed. The bends are stiffened by hardening or compacting the metal therein, as indicated by heavy shading between lines 5, 6, in the magnified detail view, Fig. 3, while the connecting portions are softer and more flexible. The diaphragm 1 is provided with a flange 7, which permits it to be clamped between the rim of a diaphragm-casing 8 and a ring 9 by screws or bolts 10. The central portion of the diaphragm receives a push rod or stud 11 for transmitting its movement to a balanced damper lever 12, adjustably supported on a rocker 13 which sits on a spider frame 14 rising from ring 9. The movement of the lever opens and closes a furnace door or damper 15 which is connected thereto by a chain in the usual manner. With the diaphragm chamber in communication with the steam space of the boiler, for example, the diaphragm will follow the fluctuations in the pressure, but for a given pressure on the underside of this collapsible diaphragm, the movement of the central part of the diaphragm will be materially larger than in the case of a diaphragm in which the bends of the folds are relied on for giving flexibility. The reason for this will clearly appear in the description of the form of diaphragm having plain parallel connecting portions, next to be described.

In Fig. 4, the collapsible diaphragm which closes one side of a thermosensitive vessel 16, suitable for use in a steam trap, for instance, is constructed with annular convolutions having their curved ridges 2, 3, connected by plain concentric rings 4 or portions of plain cylinders, the length or height of these latter portions being of suitable extent to secure collapsing and extensible action by substantially their own movement. The density of the sheet may be the same throughout, or it may be increased at the bends, as above described. Assume the vessel contains an expansible fluid, and that its pressure has increased above the pressure when the diaphragm is in normal position with its side folds parallel. Besides the force exerted by the fluid pressure tending to force the diaphragm outward, there is a force set up against the annular walls of each fold, as indicated by arrows 17, 18. These pressures are opposite, but are not equal since the area of the wall more remote from the center is greater than that nearer the center. There is therefore a resultant pressure on each fold acting in toward the center of the diaphragm. As soon as the diaphragm begins to yield outward under the initial action of the pressure in direction along the normal axis of the diaphragm, then there is a normal component of this centrally directed pressure which is

added to the fluid pressure acting normally on the surface of the diaphragm, as indicated in the parallelogram of forces at 19. This outward component increases in magnitude as the side of the fold departs from its normal position, thereby enabling the diaphragm to exert a greater outward force than a diaphragm of the same diameter which relies on flattening its bends to secure outward movement, the limit of which is quickly reached if this movement is to be kept within the elastic limits of the metal in the diaphragm. It is also to be observed that inward buckling under the resistance offered by the work through the rod or stem attached to the diaphragm is guarded against, and lost motion practically obviated by the more advantageous position of the folds to resist this tendency.

Instead of providing the folds with parallel sides normal to the surface, they may be parallel but inclined, as shown in Fig. 5; otherwise the construction is the same and also the mode of operation, as described with reference to Fig. 4. 90

What is claimed is:—

1. A diaphragm for use with fluid pressure, consisting of a sheet of metal provided with a plurality of annular convolutions, the bends of which are connected by flexible annular portions in which motion is substantially confined when the diaphragm is subjected to fluid pressure to bend it out of its normal plane. 95

2. A collapsible diaphragm for use with fluid pressure, consisting of a sheet of metal provided with a plurality of annular convolutions, the bends of which are stiff and are connected by flexible annular portions in which motion is substantially confined when the diaphragm is subjected to fluid pressure to bend it out of its normal plane. 100

3. A collapsible diaphragm for use with fluid pressure, consisting of a sheet of metal provided with a plurality of annular convolutions, the bends of which are of compacted metal and are connected by flexible annular portions in which motion is substantially confined when the diaphragm is subjected to fluid pressure to bend it out of its normal plane. 110

4. A diaphragm for use with fluid pressure, consisting of a sheet of metal provided with a plurality of annular convolutions, the bends of which are connected by parallel flexible annular portions in which motion is substantially confined when the diaphragm is subjected to fluid pressure to bend it out of its normal plane. 120

5. A diaphragm for use with fluid pressure, consisting of a sheet of metal provided with a plurality of annular convolutions, the bends of which are connected by parallel flexible annular portions inclined to the face of the diaphragm and in which 125

motion is substantially confined when the diaphragm is subjected to fluid pressure to bend it out of its normal plane.

6. A flat diaphragm having collapsible and extensible annular convolutions portions of which are flexible and other portions more or less inflexible.

7. A flat diaphragm subject to fluctuations of fluid pressure, the same consisting of a sheet of metal provided with a plurality of concentric convolutions consisting of oppositely disposed trough portions connected

by concentric ring portions which latter are adapted to receive and resolve lateral fluid pressure thereon into an outward thrust on the diaphragm increasing as the diaphragm expands away from its normal position. 15

In testimony whereof I have signed this specification in presence of two subscribing witnesses.
